SILENCER

William A. Jack, 3d, Madison, Wis., assignor, by
mesne assignments, to C. F. Burgess Labora-
tories, Inc., Madison, Wis., a corporation of
Delaware

Application June 20, 1931, Serial No. 545,776

2 Claims. (Cl. 181—41)

This invention relates to improvements in silencers for noise-producing gases and especially silencers for the intakes and exhausts of internal combustion engines, compressors and the like.

It is an object of this invention to provide a silencer which is highly effective for low pitched sounds. It is the principal object of this invention, however, to provide a muffler or silencer which is equally effective in removing both low and high pitched sounds. Further objects will become apparent when the following description is read in conjunction with the accompanying drawings in which:

15 Figs. 1 to 10 show in cross section various types of silencers embodying the inventions of this application.

Silencers for noise-producing flowing gases, such as are encountered in engine intakes and 20 exhausts are based on various principles. The silencer most commonly encountered is based on the baffle principle. This type of silencer, although it silences effectively, builds up a back-pressure which is undesirable for many purposes. In a second type the duct through which 25 the gases pass is lined with a sound-absorbing or a gas-pressure absorbing and sound-absorbing material along which the gases pass. There is practically no increase of back-pressure due to 30 this method of sound absorption. If the duct is curved or bent the back-pressure increases due to the change in the direction of the gases. This second type of silencer is described in the Schnell Patent No. 1,811,762, granted June 23, 1931. This 35 type of construction gives excellent results for most purposes but has the disadvantage of not being as effective on low-frequency sounds, especially those below 400 cycles per second, as on high-frequency sounds. These sounds usually 40 are not as objectionable as the high-frequency sounds. Although the absorbing materials used in the Schnell silencer vary in their effectiveness with sounds of different frequencies none have proved highly effective with the low notes. Ab- 45 sorbing materials having very small openings have proved most effective but these are undesir- 50 able for engine exhausts since the fine holes are easily clogged by the carbon deposited by the gases. Lengthening the silencer is effective but this is undesirable from the standpoint of cost and increased back-pressure due to increased 55 surface friction.

It is possible to remove low notes, as well as high notes, from moving gases by means of acoustic filters or neutralizers. These have been

used in various forms for neutralizing sounds of various kinds. The difficulty which is encountered in the removal of sounds of a wide range of frequencies is that the apparatus becomes very cumbersome and costly since each neutralizer or filter is effective over a narrow band of frequencies. Since the absorbing type of silencer is effective over a wide range of frequencies, I have found that I can supplement this absorber type of silencer with a neutralizing type effective over a narrow band of low frequencies and, thus effectively silence the entire range of frequencies.

The filters or neutralizers for low frequencies do not need long tubes but are effective with very short lengths so that the silencer may be kept 15 within reasonable dimensions. I have further discovered, as will be explained more in detail hereinafter, how to silence most effectively by the combination of absorber and neutralizer either the low frequencies or higher frequencies 20 when both are present and it is desirable to remove both from the moving gas.

In the forms of the invention herein illustrated,

Fig. 1 shows a simple type of acoustic filter or 25 neutralizer combined with sound-absorbing material. A substantially imperforate casing 10 is employed. This casing has a sound inlet opening 11 and a sound outlet opening 12. These may be reversed so that 11 is the outlet and 12 the 30 inlet, though the first arrangement is preferred for some types of construction. A duct 13 extends from one of the openings toward the other opening. This duct has walls of sound-absorbing 35 and sound-absorbing material 14 of the character described in the Schnell patent. If the absorbing wall is not made of a molded structure, a foraminous tube 15 is required to face the absorbing material 14. This foraminous tube may 40 be of screen, wire mesh, perforated metal and the like as described in the Schnell patent, so that the sounds and gas-pressure waves will reach the absorber. For engine and compressor intakes flamable absorbers such as cotton, wool, hair-felt, wood fiber and the like may be used, whereas for gas engine exhausts and other hot gases there may be used non-flamable absorbers such as steel-wool and other metallic wool, exfoliated vermiculite, asbestos fibers, rock wool, pumice, Haydite and other loose ceramic aggregates. The aggregates may, however, be bonded together to leave intercommunicating absorbing channels. An exterior retaining wall 16 for the absorber is used with loose absorbers or for those 55

that may disintegrate. However, this retaining wall is not required and may be omitted where the absorbing material is such that this may be done. The absorbing material may be as thin as $\frac{1}{4}$ inch but preferably should be at least $\frac{1}{2}$ inch thick to be most effective in absorbing sounds and gas-pressure peaks. A chamber 17 is left between the casing 10 and the absorber 14. The low pitched sounds are neutralized in this chamber. A substantial opening 19 is left between the absorbing wall 14 and the end wall 18 of the outer casing. The opening 19 permits the sounds in the gas, and especially the low-frequency sounds passing through duct 13, to pass into annular chamber 17 where they are neutralized. Opening 19 need not be entirely open as shown. By extending the foraminous tube 15 to the end wall 18, as shown in Fig. 2, the same effect may be obtained.

The diameter of duct 13 may vary with respect to opening 11. If it is the same size as that of opening 11 the length of absorbing duct 13 is less than that of casing 10 as shown in Figs. 1 and 2. The length of duct 13 with respect to casing 10, the volume of annular chamber 17 and the other dimensions determine the neutralizing characteristics of the device and these may be adjusted so that it will neutralize sounds of a certain band of low frequencies. As an example, in an acoustic filter or neutralizer in which absorber 14 was omitted, tube 15 (Fig. 1) being unperforated, in which casing 10 was $3\frac{1}{2}$ inches in diameter and 6 inches long, increasing the length of tube 15 from $4\frac{1}{2}$ inches to 7 inches, opening 11 being larger than the outside diameter of tube 15, greatly increased the neutralization of sounds in the 175-375 frequency band but decreased those of 375-1,500 cycles per second. Increasing the diameter of the casing 10 increases further the efficiency of neutralization of sounds in the lower frequency band. When the tube 15 is smaller than opening 11, reversal of the sound direction, so that it enters at 12, decreases the absorption of sound in this range of frequencies.

Varying the shape of either the duct or casing or both from round to oval or some other shape also varies the characteristics.

Instead of having the opening 19 to neutralizing chamber 17 at one end of duct 13 it may be provided at the center, or some other point, as is shown in Fig. 3. This provides neutralizing chambers of two different lengths in one device. By placing the duct 13 off center or making duct 13 and casing 10 of different cross sectional contours the dimensions of chamber 17 may be varied within the same apparatus and the absorbing characteristics thereof may be thereby varied.

In Fig. 4 the sound absorbing wall 14 or duct 13 is longer than the enlarged portion of casing 10 and the casing is provided with a co-axial reduced portion 50 into which the end of the duct extends. End wall 18 may be stepped as shown to leave annular opening 20 to allow the sounds to reach neutralizing chamber 17. The sound should preferably enter at opening 11 in this type of silencer although gases conveying the sounds may pass either way without apparently affecting the silencing characteristics of the device.

In Fig. 5 the absorber 14 or duct 13 does not extend to end wall 18 but stops short thereof. If a foraminous tube 15 interiorly lines duct 13 it extends only throughout the length of the absorbent lining 14. The end 21, which is optional and may be omitted, extends beyond end wall 18 and is blank or imperforate.

In Fig. 6 the absorbing material 23 is arranged interiorly of casing 10 to exteriorly line the neutralizing chamber 17. Imperforate tube 24 passes through the casing and may be varied in length, that is, it may extend beyond end wall 18 as shown or it may not extend to it, as in Figs. 1 and 2. Opening 25 allows the sound passing through tube 24 to reach neutralizing chamber 17 and absorbing material 23. This construction, though more effective for low frequencies, is not as effective for absorbing high frequencies as those in which the central duct has an absorbing wall. The two types of constructions may be combined so that both the duct and casing have absorbing walls.

In Fig. 7 the construction of Figs. 1 or 2 is modified by the insertion of a baffle 26 extending inwardly from end wall 18 to form a more tortuous or restricted and longer opening 27 for the passage of sound into neutralizing chamber 17. A similar baffle may be used in connection with opening 19 of Fig. 3, opening 20 of Fig. 4, opening 22 of Fig. 5 and opening 25 of Fig. 6. The length and spacing of baffle 26 may be varied to change the neutralizing characteristics of the device. Tests indicate that the longer the overlap of baffle 26 the lower the frequency band which is attenuated.

Many modifications of the structures described may be made. As an example, in Fig. 8 the construction of the Schnell muffler is modified by the insertion of a neutralizing chamber 28. The casing 10 with the duct 13 having absorbing wall 14 passes from end 11 to end 12. The neutralizing chamber 28 is inserted in the absorbing wall 14 and is connected with duct 13 by opening 29. The characteristics of the neutralizer may be varied by the size and shape of the chamber and by the insertion of baffle 30 to provide a more tortuous or longer passage 31 for the sounds to reach the chamber 28. Portions of the walls or all of the walls of the chamber 28 may be of absorbing material. This is accomplished readily by making the walls of foraminous material 32 as shown.

In the modification of Fig. 9 the neutralizing chamber 17 is combined with the absorbing material 14 in end-to-end relation instead of in an annular relation. The neutralizing chamber preferably is also lined with an absorber 33.

In the application of my invention to a special situation in which it was necessary to change the direction of gas flow due to limited space, the device of Fig. 10 was found satisfactory. The direction of gas flow and sound propagation is in opposite directions as indicated by the labeled arrows. With duct 13 having absorbing wall 14 open at both ends the low-frequency sounds were not silenced, though the high-frequency sounds were removed satisfactorily. Duct 13 was then closed at the left end with a piece of sheet steel and the low frequency notes were then neutralized. By shutting off the duct at 34, as shown by the dotted line, the low-frequency sounds were again in evidence. An absorbing wall at the left end instead of sheet steel did not decrease the low-frequency neutralization. It appears therefore that a sound-absorber for high frequencies (above about 500 cycles per second) when used to line a neutralizing chamber, although it presents an absorbing surface where the sound wave apparently must be reflected, does not interfere with the neutralizing action of the chamber, to which it also adds an absorbing effect.

As will be apparent to those skilled in the art,

many variations of the constructions described in the specific disclosures may be made.

Where the interior diameter of duct 13 is equal to that of the end opening 11 the noise may be passed in either direction with equal silencing but where the duct diameter is less than the opening, as in Figs. 4 and 5, the operation is more effective when the noise entrance is at 11.

Although the construction of most of the forms of my device shows the channel from duct 13 to the neutralizing chamber 17 to be adjacent to the end wall 18, it is understood that this channel may be placed at either end or at any predetermined point along the duct as in Fig. 3. The casings and ducts may be of varying shapes and the ducts need not be placed concentric with the casings. The casings may also vary in size from end to end. These variations may be similar to those shown in Fig. 3 at Figs. 8 to 11 of United

20 States Patent No. 1,811,322 to F. H. Schnell.

In instances where it is known that harmonics of low-frequency fundamentals exist in the source of sound to be muffled, then the application of acoustic filters to remove first the fundamental 25 may cause certain harmonics to build up excessively, these harmonics being of high frequency. Partial muffling by absorption following the acoustic filter or neutralizer may still leave nearly as much intensity in the harmonic as originally existed with no muffler. In this case it is preferable to allow the absorption muffler to act first on the sound to be silenced. Conversely, however, it is possible for the absorption muffler to build up at low frequencies and thus make the 30 apparent effect of the following acoustic filter less than it actually is. Therefore, it is possible for one effect to cancel the other and the order of mufflers makes no difference on the intensity of the overall sound, although it makes a difference 35 in pitch, the first case giving a resultant high pitch, and the second a low pitch. The relation between the periods of the two types of mufflers and their muffling efficiency determines the resultant overall sound (which is equal, regardless 40 of order, for one special case only). The proper order has to be determined for the case at hand. In the case of non-existence of harmonics, or in other words the existence of a low frequency fundamental and non-harmonic high frequen-

cies, it is preferable to place the acoustic filter first to prevent the absorber muffler from building up the low frequency due to the before-mentioned resonance effects.

Since gas-engine exhausts consist of a rapid 5 succession of gas pulses, such exhausts are not unlike sounds which are a rapid succession of gas pressure waves. However, the gas pulses in the exhaust are of comparatively low frequency and therefore may be compared to low-frequency 10 sounds. Data show however that these are not entirely alike, especially in their action on sound absorbers. Because of this relationship between 15 sound pulses and gas-pressure pulses the principles of my invention may be applied to both but due regard must be given to the differences that have been mentioned when applying these principles in practice.

I claim:

1. A silencer comprising a substantially im- 20 perforate casing having two openings therein, a duct for the sound to be silenced having a wall and a surrounding layer of sound-absorbing ma- 25 terial, a space between said sound absorbing ma- terial and said casing, said wall extending from one of said openings into the second of said open- 30 ings, the cross sectional area of said duct excluding said absorbing material being sufficiently smaller than the area of at least a portion of said second opening to provide a passage between said duct and the wall of said second opening, said passage providing communication between said space and said second opening.

2. A silencer comprising a substantially im- 35 perforate casing having two openings therein, a duct for the sound to be silenced having a wall extending from one of said openings into the second of said openings, the cross sectional area of that portion of the wall of said duct extending into the second of said openings being sufficiently 40 smaller than the area of said second opening to leave a substantial opening therebetween, at least a portion of said wall not extending into said second opening comprising sound-absorbing ma- 45 terial, the balance of the wall of said duct being imperforate, and a space between said wall of ab- sorbing material and said casing.

WILLIAM A. JACK, 3RD.
